VENETIAN BLIND

August T. Victorl, Pawtucket, R. I., assignor to
Arcraft Venetian Blind Company, Hazleton,
Pa.

Application March 16, 1934, Serial No. 715,984

1 Claim. (Cl. 156—17)

This invention relates to improvements in Venetian blinds, the general object of the invention being to provide means whereby the slats can be readily tilted to various positions from horizontal positions.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:—

Figure 1 is an enlarged view of the upper corner of a window, showing the means for adjusting the tilt of the slats.

Figure 2 is a vertical sectional view through the upper part of the blind.

Figure 3 is a view of one of the brackets shown in Figure 1.

Figure 4 is a view of the pinion carrying bracket.

Figure 5 is an edge view of Figure 4.

Figure 6 is a view showing the means for supporting the pulley bar in a corner of the window frame.

Figure 7 is a section on line 14—14 of Figure 6.

In the drawing, a portion of a window frame is shown at A and the pulley bar of the blind or shade is shown at 1 and is supported in the upper part of the frame by the brackets, one of which is shown at 2. The tapes or flexible strips of the blind or shade are shown at 3 and the operating cords at 7. These cords, pass through the openings 11 in the slats 12 of the blind, these slats being connected to the cross pieces 13 which connect the strips or tapes of each pair of tapes or strips together, as more clearly shown in Figure 2. These cords pass into the groove 14 of the pulley bar and over the pulleys 15 carried by the bar and extend downwardly adjacent one side of the window.

A bracket 18 is fastened in the upper left hand corner of the window frame and is provided with

the perforated ears 19 which form bearings for a shaft 20 having a worm 21 thereon and with a pulley 22 connected to one end thereof. The cord 23 passes over this pulley so that by pulling one end of the cord, the shaft is rotated in one direction and by pulling the other end, the shaft is driven in the other direction and the two parts of this cord pass through the eyes 24 in the horizontal part 25 of the bracket 18. A second bracket 26 is fastened to one end of the top rail 10 27 and carries the stub shaft 28 which finds a bearing in the hole 29 in the bracket 18, the shaft carrying a gear 30 which meshes with the worm 21 so that rotation of this worm 21 will rock the top rail 27 in either direction from a horizontal 15 position, in accordance with the direction of rotation of the shaft 20, and thus the slats 12 will be tilted in one direction or the other, due to the lifting of one tape or strip 3 of each pair and the lowering of the other strip or tape of each pair.

It is thought from the foregoing description that the advantages and novel features of the invention will be readily apparent.

It is to be understood that changes may be made in the construction and in the combination and arrangement of the several parts, provided that such changes fall within the scope of the appended claim.

What is claimed is:—

In a Venetian blind including a top rail, a bracket connected to one end of the top rail and having a pinion attached thereto, a second bracket attached to a stationary member, a pair of spaced horizontal arms on the second bracket extending to a point above the first bracket and said second bracket having a hole therein located below the arms for receiving a part of the first bracket, a shaft journaled in the arms of the second bracket and having a worm thereon engaging the pinion, a pulley on the shaft, a cord, passing over the pulley and depending therefrom, said second bracket having a horizontally arranged part connected with its lower end, said part having a pair of spaced holes therein through which the two parts of the cord pass.

AUGUST T. VICTORL.
